UNITED STATES PATENT OFFICE.

SAMUEL ANDERSEN, OF EAU CLAIRE, WISCONSIN.

BUILDING BLOCK.

1,413,562.

Specification of Letters Patent. Patented Apr. 25, 1922.

Application filed August 23, 1920. Serial No. 405,336.

To all whom it may concern:

Be it known that I, SAMUEL ANDERSEN, a citizen of the United States, residing at Eau Claire, in the county of Eau Claire and State 5 of Wisconsin, have invented certain new and useful Improvements in Building Blocks; and I do hereby declare the following to be a full, clear, and exact description of the invention, such as will enable others skilled in 10 the art to which it appertains to make and use the same.

The object of my invention is to provide an inexpensive efficient building block suitable as a unit for constructing walls and 15 having side surfaces especially adapted to hold wall plaster.

Generally stated, the invention consists of the novel devices and combinations of devices hereinafter described and defined in the 20 claims.

It is a well known fact that small bits of lumber in a mill or elsewhere are usually wasted or used for kindling. My invention provides an important use for such odds and 25 ends.

The invention is illustrated in the accompanying drawings, wherein like notations refer to like parts throughout the several views.

30 Referring to the drawings:—

Fig. 1 is a perspective view of a portion of two adjoining walls made from my improved building blocks;

Fig. 2 is a perspective view of a single 35 block;

Fig. 3 is a plan view of a similar block; and

Fig. 4 is a fragmentary view with parts broken away of two adjoining blocks showing 40 my locking key inserted.

The numeral 5 indicates the lengthy tie members of my building block and 6 the short transverse cross members, which project slightly beyond the lengthwise edges of said 45 tie members 5, affording grooves 7 by their said projections. The tie members 5 are spaced widely apart to use as little lumber as possible and still assure a strong block. The cross members 6 are spaced slightly 50 apart to form chinks 8 on the sides of the wall which, with the said grooves 7, furnish a good surface for plaster to cling to.

The successive layers of my block are nailed upon each other by nails 9 or in any 55 other suitable way. In the process of this nailing, the end of each layer is carefully

set back a trifle on the layer beneath, thus giving an oblique step arrangement to one end of the block, and, since the tie members are of equal length, a complementary projecting arrangement results at the opposite end of said block. When a wall is built, the projectingly arranged end of one block is set on the stepped end of another block and the successive steps and projections exactly fit. 60 65

A key 10 is inserted between the adjacent tie members 5 of two joined blocks, as shown in Fig. 4, and locks said blocks together, giving them the necessary solidity.

When a vertical end is needed for the ends 70 of a wall or for a window casing 11, the block may be sawed off to form a flat vertical end, as desired.

In building a wall, the blocks are put down in layers like bricks, with their lapping 75 edges fitting snugly together, and keys are fitted to the adjoining blocks of each layer.

Such a construction makes a strong substantial wall having both its sides well adapted to hold plaster, suitable for outside 80 or inside use. The expense of such a construction is little, for waste odds and ends are used in the making of my blocks.

What I claim is:—

1. A unit building block having complementary oblique ends fitting snugly and tightly with their respective complementary ends of other similar blocks to form a wall, said block comprising layers of long tie members and layers of short transverse cross 90 members projecting slightly beyond the longitudinal edges of the said tie members and forming grooved side surfaces adapted to receive plaster.

2. In a building block, several alternate 95 layers of lengthy tie members and several alternate layers of short transverse cross members projecting slightly beyond the lengthwise edges of said tie members to form grooved surfaces for plaster on the 100 two opposite sides of said block, means for fastening the said members together with the ends of the successive layers slightly set back on each other to form an oblique stepped arrangement at one end of said block, and a complementary oblique projecting arrangement at the opposite end of said block enabling both ends of said block to 105 fit perfectly into the complementary ends of similar blocks.

3. In a building block, several alternate 110 layers of lengthy tie members and several

alternate layers of short transverse cross members projecting slightly beyond the lengthwise edges of said tie members to form grooved surfaces for plaster on the two opposite sides of said block, means for fastening the said members together with the ends of the successive layers slightly set back on each other to form an oblique stepped arrangement at one end of said block, a complementary oblique projecting arrangement at the opposite end of said block enabling

both ends of said block to fit perfectly into the complementary ends of similar blocks, and a locking key fitting between the adjacent tie members of two joined blocks to lock 15 said blocks and hold them in position.

In testimony whereof I affix my signature in presence of two witnesses.

SAMUEL ANDERSEN.

Witnesses:

LOUIS J. RUHE,
EARNEY KOGER.
